UNITED STATES PATENT OFFICE.

HEZEKIAH LATSHAW, OF WOLCOTTSVILLE, NEW YORK.

CONNECTING DEVICE FOR WINKER-STRAPS.

SPECIFICATION forming part of Letters Patent No. 270,958, dated January 23, 1883.

Application filed July 3, 1882. (No model.)

To all whom it may concern:

Be it known that I, HEZEKIAH LATSHAW, of Wolcottsville, in the county of Niagara and State of New York, have invented a certain 5 new and useful Connecting Device for Winker-Straps; and I do hereby declare that the following is a full, clear, and exact description thereof, reference being had to the accompanying drawings, and to the letters of reference 10 marked thereon, making a part of this specification.

My invention relates to an improved device 15 for connecting the supporting-straps with the bridle-blinds or winkers in a set of harness. Its object is to remedy the constant breaking of 20 the winker-strap, due to the weakening thereof along the line of stitching by which it is ordinarily secured to the blind, and to insure a firm, secure attachment, which shall leave the 25 strength of the strap wholly unimpaired.

It consists of a metallic clamp which is 30 adapted to clasp the strap and to be riveted thereto and to the blind, as well as engaged by the stitching which unites the inner and 35 outer facings of the blind.

In the accompanying drawings, Figure 1 is 40 an elevation of a bridle-blind or winker and of the strap supporting its front end. Fig. 2 is a view in elevation of the rear or under side 45 of the corner of the blind to which the strap is attached; Fig. 3, an elevation of the metallic clasp detached; Fig. 4, a central longitudinal section in line $x-x$ of Fig. 3, and Fig. 5 a transverse section in line $y-y$ of Fig. 4.

A is a bridle-blind or winker; B, the winker-strap by which the front end of the blind is 50 stayed and connected with the head-piece of the bridle; C, a metallic clasp for connecting the strap to the blind. This clasp is cast of 55 malleable iron, brass, or other suitable material, in the form shown in Figs. 3 and 4 of the drawings. Its upper end, d , is concaved to receive the round body of the strap B, and is

formed with two arms or lugs, e , Figs. 2, 4, and 5, projecting laterally therefrom on each 45 side thereof, adapted to be bent over upon the strap laid in the concave seat, and thus bind and clasp it closely. A pin, f , is formed centrally within the concave seat to project transversely through the body of the strap below 50 the clasping-arms, so as to complete the secure engagement of the strap with the clasp. The lower end of the clasp is made in the form of an open frame, g , Fig. 3, from the lower bar of which a pin, h , Fig. 4, is made to project 55 centrally to pass through the body of the inner facing of the blind.

In attaching the clasp to the blind the frame g is laid between the inner and outer facings of the blind at the upper outer corner thereof, 60 and the pin h being passed through the inner lining and riveted, the two facings are stitched together in the customary manner, the stitches carried through the opening in the frame, serving, in connection with the riveted pin h , to 65 secure it firmly in place.

The clasp may be nickel-plated, and thus impart a very neat finish to the blind.

I claim as my invention—

A device for connecting the winker-strap 70 with its winker or bridle-blind, constructed in one piece and consisting of a body, d , adapted to embrace and clasp the end of the strap, an open frame, g , adapted for insertion between the facings of the blind to be held by the 75 stitching thereof, and pins f h , for piercing respectively the strap and blind, substantially as herein set forth.

In testimony whereof I have signed my name to this specification in the presence of two sub- 80 scribing witnesses.

HEZEKIAH LATSHAW.
